United States Patent Office.

GEORGE PURRINGTON, JR., OF NEW YORK, N. Y., AND JAMES H. PURRINGTON, OF MATTAPoisETT, MASSACHUSETTS.

Letters Patent No. 60,785, dated January 1, 1867.

IMPROVED CARPET-SWEEPER.

The Schedule referred to in these Letters Patent and making part of the same.

TO ALL WHOM IT MAY CONCERN:

Be it known that we, GEORGE PURRINGTON, Jr., of the city, county, and State of New York, and JAMES H. PURRINGTON, of Mattapoisett, in the county of Plymouth, and State of Massachusetts, have invented a new and useful Improvement in Carpet-Sweepers; and we do hereby declare that the following is a full, clear, and exact description thereof, which will enable others skilled in the art to make and use the same, reference being had to the accompanying drawings, forming part of this specification, in which—

Figure 1 is a vertical cross-section of our improved carpet-sweeper taken through the line *z z*, fig. 4.

Figure 2 is an end view of the same.

Figure 3 is a detail sectional view of the same taken through the line *y y*, fig. 2.

Figure 4 is a longitudinal section of the same taken through the line *z z*, fig. 2, the middle part being broken away to show the construction.

Similar letters of reference indicate like parts.

Our invention has for its object to so improve the construction of carpet-sweepers as to make them more durable, and more reliable in operation. And it consists, first, in the combination and arrangement of the caged or corrugated wheel and two adjustable wheels with each other, and with the brush-shaft and frame of the sweeper; second, in the adjustable axles or bearings, in combination with the drive-wheels and frame of the sweeper; the whole being constructed and arranged as hereinafter more fully described.

A is the frame of the sweeper, to the upper edges of which is attached the roof-shaped cover, B. C is the brush-shaft, to which the brush H is attached in the ordinary manner, and which is pivoted to the adjustable bearings D, which are secured to the end pieces of the frame A by screws passing through slots in said bearings, and screwing into said end pieces, as shown in figs. 2 and 4. To the bearings D are also pivoted the branched ends of the iron frame, E, to which the handle, F, is attached. G are the dust pans, which are pivoted to the end pieces of the frame, A, in such positions as to receive the dust and dirt raised by the brushes H, and which are held in their places by the catches I, attached to the sides of said pans, and catching upon the side pieces of the frame A. J are the drive-wheels, which are small wooden or metallic wheels surrounded with thick rubber bands, and which revolve upon axles or bearings K, the plates of which are adjustably attached to the end pieces of the frame A, and which are secured in place by screws, the lower ones of which pass through slots in the lower parts of said bearings, as shown in fig. 2, so that the said drive-wheels J may be adjusted to compensate for their wear, and may be always kept in a proper working position with respect to the other parts. The drive-wheels J must be so placed as to project a little below the lower edges of the frame, A, so as to come in contact with the carpet over which the sweeper is drawn, and be revolved by said contact. L is a small toothed or corrugated wheel, placed upon or attached to the end of the brush-shaft C, and which comes in contact with and is revolved by the drive-wheels J, and carries with it the brush-shaft C. M is a shoe placed upon the lower edge of the end piece of the frame A, opposite to the drive-wheels C, upon which that end of the sweeper slides, and which keeps the sweeper in a horizontal position while being used.

We do not claim any of the parts the subject-matter of the patents granted to Daniel Harris, October 5, 1858, and S. W. Smith, January 18, 1859, but what we do claim is—

The adjustable axles or bearings K, constructed and arranged substantially as herein described, in combination with the drive-wheels J, and frame A, of the sweeper, as and for the purpose herein set forth.

GEO. PURRINGTON, JR.,
JAMES H. PURRINGTON.
